UNITED STATES PATENT OFFICE.

MARVIN EARL STEGER, OF McCLEARY, WASHINGTON.

MACHINE FOR PATCHING PITCH POCKETS.

Application filed October 5, 1923. Serial No. 666,796.

To all whom it may concern:

Be it known that I, MARVIN E. STEGER, a citizen of the United States, residing at McCleary, in the county of Grays Harbor 5 and State of Washington, have invented a new and useful Machine for Patching Pitch Pockets, of which the following is a specification.

The invention resides in the provision of 10 an automatic machine for removing defects from lumber and for applying a suitable patch of good lumber to the place from which the defect has been removed.

In the manufacture or milling of doors 15 or like structures from Douglas Fir or similar kinds of lumber, much difficulty is encountered due to the presence in such wood of numerous defects, principally pitch pockets, which make it necessary to discard thousands of feet of lumber as useless, or to 20 endeavor to practically patch such defects, by removing the defect and substituting an inlay of sound wood.

It has become the common practice in this 25 art to thus patch the stock by hand and it will be readily understood that, while a saving of thousands of feet of stock is thus effected this operation is a tedious one and very costly, due to the great number of 30 workmen necessary to carry out the various operations, also, as in the case of all operations wholly manual in their nature, production is limited.

One such method is to have one man to 35 cut out the pitch pocket or other defect, by hand or by automatic tool for that purpose alone, and to have him pile the stock on tables. Another man is kept busy cutting patches to be inserted into the places from 40 which the defects have been cut, and two additional men are kept busy removing the stock from the tables, taking small brushes and gluing the grooves or cut-out pockets, laying aside the brushes and taking the cut 45 patches or plugs from boxes where they have been placed by the cutter, inserting them into the grooves by hand under the urge of a mallet, and finally by dressing down the plugs with block planes as some of the plugs

do not fit properly. Thus it will be seen that 50 at least four men are required at one point of operation and whose production of finished product is greatly limited by reason of the manner and nature of the operations they must perform. 55

Therefore it is the primary object of my invention to provide a wholly automatic machine for cutting out pitch pockets or other defects from lumber and for inserting and gluing patches of clear lumber into the pockets 60 from which the defects have been cut and also for suitably trimming the said patches.

In its more detailed nature, the invention has for its object to provide a machine of 65 the type stated and in which means is also provided for quickly and effectively adjusting the machine for applying varied sizes of patches and in which means is also provided for adjusting the defect removing 70 mechanism to ensure perfect sized pocket cutting and for compensating for wear of such mechanism so as to provide for perfect cooperation of the pockets and the patch plug dimensions at all times. 75

With the above and other objects in view that will hereinafter appear, the invention also resides in those novel details of construction, combination and arrangement of parts, all of which will be first fully described, then be specifically pointed out in the appended claims, reference being had to the accompanying drawings, in which:

Figure 1 is a right side elevation of the invention, the parts being at the inoperative position. 85

Figure 2 is a left side elevation of the machine, the parts being similarly positioned in Figure 1.

Figure 3 is a plan view of the machine. 90

Figure 4 is a front elevation of the machine.

Figure 5 is a diagrammatic right side elevation illustrating the normal movement of the levers and the parts there illustrated in 95 effecting the short patch.

Figure 6 is an enlarged detail right side elevation of the feed box actuating rocker

cam and the means for locking and releasing the same, the table lock detent mechanism being also shown.

Figure 7 is a detail section on the line 5 7-7 of Figure 5.

Figure 8 is a diagrammatic view similar to Figure 5 and which illustrates the movement of the parts during the effecting of a long patch.

Figure 9 is a diagrammatic left side elevation illustrating the cooperation of the chip breaker with the stock to be patched and the saw.

Figure 10 is a view similar to Figure 9 15 and illustrates the movement of the chip breaker as the saw is moved forward.

Figure 11 is a detail right side elevation 20 illustrating the plunger carrying plates and the mechanism for locking the driving block to cause movement thereof and for releasing the same from movement.

Figures 12, 13, 14 and 15 are diagrammatic perspective views illustrating a pitch pocket or defect, showing the same removed 25 by the saw, showing the appearance of a patch as applied, and showing a section through the patch as applied and illustrating its relation with the cut out formed by the saw.

Figure 16 is a diagrammatic view showing in full lines the manner in which a short defect is removed and in dotted lines the removal of a long defect.

Figure 17 is a somewhat diagrammatic 35 right side elevation of the table supporting standard and the mechanism for lifting the table and for returning it to its lowered position, opposite positions of the parts being illustrated in full and dot and dash lines.

Figure 18 is a left side elevation of the 40 main movable clutch box.

Figure 19 is a cross section taken on the line 19-19 on Figure 18.

Figure 20 is a plan view of the clutch box 45 adapted to be movable with the main table.

Figure 21 is a cross section taken on the line 21-21 on Figure 20.

Figure 22 is a detail perspective view of the saw head supporting bracket.

Figure 23 is a plan view of patch plug 50 transferring deck, the cutter knife and the actuating mechanisms therefor, the plug transfer position being shown in dot and dash lines.

Figure 24 is an enlarged section taken on the line 24-24 on Figure 23.

Figure 25 is a detail plan view of a modification of transfer deck abutment plate and plunger structure.

Figure 26 is an enlarged detail cross section taken through the transfer deck abutment plate and the spring pressed plug holding plate cooperative therewith.

Figure 27 is an enlarged elevation of the

cutter knife mechanism, parts of the wall of 65 the main table and the knife slide operating detent being shown in section.

Figure 28 is an enlarged end view of the parts shown in Figure 27, part of the transfer deck and the main table shelf being 70 shown in section.

Figure 29 is a detail cross section illustrating the lateral adjustability of the plunger head.

Figure 30 is a diagrammatic view illustrating the manner in which the individual patch plugs are severed from the patch stock strip and the relation of the plug with the portion removed by the saw.

Figure 31 is a detail cross section taken 80 through the glue box.

Figure 32 is an enlarged detail plan view illustrating the retractable detent of the knife slide operating lever.

Figure 33 is a detail view of the rock 85 cam arm.

In the drawings, in which like numerals of reference indicate like parts in all of the figures, 1 represents the base structure upon which the various mechanisms of the invention are mounted.

A standard 2 is secured upon the base 3 and is adapted to support the work table 3 which is vertically movable, by reason of being slide and guide connected as at 4 to the standard 2, so that it may be moved upward with the stock to be patched thereupon to effect the operations necessary to remove the defects from such stock and for inserting and fixing sound patches thereinto, in a manner soon to be described.

A pair of toggle levers 5 cooperate with the slide portion of the table 3 for the purpose of lifting the same to its operative position, and the toggle levers 5 are secured to the slide as at 6, secured to each other as at 7, and the remaining end of the adjacent one thereof is fixedly secured to a rock shaft 8 mounted in suitable bearings fixed to the base 1 so as to be moved with the shaft when it is rocked in a manner soon to be described, see Figures 4 and 17.

A release pedal 9 is mounted in suitable bearings secured to the base 1 in a manner whereby the lock end 10 thereof will engage 115 a lock cam 11 secured upon the shaft 8 in a manner whereby the said release pedal will prevent the rock shaft 8 from rotating in the direction in which it normally tends to rock under the influence of the lever 12 fixed upon the said rock shaft and provided with an adjustable weight 13.

Four uprights or supporting standards 14 are secured to the base 1 so as to form a supporting medium for a pair of parallel track rods 15 secured in the upper ends of the opposing pairs of standards 14 and each opposing pair of uprights 14 are provided with

a cross brace 16, the latter serving to support a stationary sub-table or shelf 17, see Figures 1 and 4.

A main table 18 is supported, through the medium of a plurality of bearing rollers 19 fixed thereto, to be slightly movable along the guide rods 15 in a manner and for the purpose later to be described, and a pair of oppositely disposed pendent anti-jump brackets 20 are fixed to the bottom of said table to prevent dislodgement of the table from the said guide rods 15. The brackets 20 also act as abutments for engaging stop brackets 21 secured to the guide bars 15 and 16 adapted to limit movement of the table in that particular direction for a purpose which will be later apparent.

A supporting wall or bracket 22 is supported above the base 1 by end supports 23 secured to the base. This wall 22 is provided with a long slot 24 adapted to guide a master cross head block 25 reciprocable therein, by reason of its pivotal connection with the pitman 26 and the cooperating pivotal connection of that pitman with the crank disk 27 secured upon to rotate with the cross shaft 28 rotatable in suitable bearings 29 fixed to the base 1.

A driven cross head or block 30 is also reciprocable, at times, in the longitudinal slot 24 and the last named cross head block has a pair of scissors action gripper dog clutch members 31 pivoted thereto as at 32 and having the cross ends 33 thereof spring connected as at 34 to tend to force the gripper dogs toward each other in gripping relation.

The ends 33 of the gripper dogs are shaped cam-like as at 35, so as to cooperate with the head of a spreader cam 36 to be spread thereby to normally hold the dogs 31 to the out-of-clutch position. The spreader cam 36 is suitably guided as at 37 in guides fixed to the wall 22 and is provided with a reduced portion around which takes a coil spring 38 which acts, against the shoulder of the spreader cam and a bracket fixed to the wall 22, to normally force the said cam to the position illustrated in Figure 1.

A pair of toggle links 39 is pivoted one to the spreader cam 36, the other to one of the guide brackets 37 and together to a toggle breaking lever 40 (pin and slot connected as at 41 to the wall 22 and provided with a heel 42 adapted to be engaged by a heel portion 43 of a bell crank lever 44 fixed upon the shaft 8 to rock therewith) so that when the said shaft is rocked under action of the weight 13 the toggle 39 will be broken and the spreader cam 36 retracted from the position illustrated in Figure 1. The other end of the bell crank 44 is provided with a reset effecting toe 45 hereinafter again referred to.

A large diameter gear 46 is also fixedly

secured upon the cross shaft 28 and rotary motion is imparted to this shaft 28 by reason of this gear 46 being driven by a pinion 47 secured upon another cross shaft 48 also having bearing in the bearings 29 which support the cross shaft 28. The cross shaft 48 is driven through the medium of a large diameter pulley 49 over which takes a driving belt 50 driven by a small pulley 51 on the drive shaft of the power motor 52 supported as at 53 upon the base 1.

From the foregoing description, it will be readily apparent that when one depresses the foot lever 9, therefore releasing its locked relation with the cam 11 and permitting the weight 13 to effect a rocking of the shaft 8, in the direction indicated by the arrow in Figure 1, that not only will the toggle links 5 be straightened to effect a lifting, to the operative position, of the work table 3, but engagement of the heels 43 and 42 will effect movement of the toggle links 39 such as will retract the spreader cam 36 and permit the dog clutch members 31 to close so as to be engaged by and carried with the master block 25 through one cycle of operation, that is, one reciprocation along the slot and back again to the position illustrated in Figure 1. While the crank disk 27 rotates continuously and thus reciprocates the master block 25 at a speed of approximately sixty strokes to the minute, it should be understood that the machine functions only through a single cycle, as before described, the automatic release of the clutch dogs 31 from the master block 25, after a single reciprocation, being effected in a manner later to be described.

A pair of opposing supporting standards 54 is secured to the bed frame 1 adjacent one end thereof, and serves to support the rock shaft 55 upon which is secured a pair of operating arms 56, one of which has a downward extension 57 which cooperates, through the medium of a pitman 58, with the driven cross head block 30 so that the arms 56 and 57 will be caused to oscillate and the shaft 55, upon which they are fixed, to rock when the said block 30 reciprocates with the master block 25 in the manner hereinbefore described. The arm extension 57 is provided with a further extension 59 which is pin and slot connected to a drag or slide bar 60 suitably guided in bearings 61 secured to the base 1 so as to be dragged along over the base as the arm extension 57 is caused to oscillate back forth through a single cycle. This drag bar 60 has pivoted thereto a spring pressed dog 62 adapted to move in the plane of position of the toe 45 of the bell crank 44. By reference to Figures 1 and 17 it will be apparent that as the drag bar 60 is moved in the direction of the full line arrow on Figure 17, the dog 62 will ride freely under the toe 45, but when the

drag bar moves in the oposite direction, indicated by the dotted arrow on that figure, the dog 62 will engage the toe 45 in a manner such as will cause a rocking of the shaft 8 5 in a direction opposite to that indicated by the arrow on Figure 1, and for the purpose of effecting a resetting of the parts to the position illustrated in said Figure 1.

For properly cutting out the pitch pockets, 10 one of which is diagrammatically illustrated in Figure 12, I provide a circular saw 63 so normally positioned and of such dimensions that, when the table 3 is moved upward to its operative position, a cutting out of the 15 pitch pocket will be immediately effected in the manner illustrated diagrammatically in Figure 16, and in a manner also for providing a standard dimension cut out portion.

The saw 63 is mounted at the end of a cross 20 shaft 64 rockably mounted in a saw head or cross bracket 65. A pair of carrier arms 66 are provided and the same have one end thereof fixed to the saw head 65 and the other end thereof mounted upon a cross shaft 25 67 secured in the upper ends of the arms 56. The arms 66, by reason of their connection with the oscillatable arms 56, serve to effect movement of the saw 63 upward out of the groove it cuts and out of the way 30 of the operator manipulating the stock to be patched, by reason of the cooperation of the saw head 65, through a bracket 68 secured thereto and which is forwardly extended and provided with a pair of lateral 35 members 69, with the cam grooves 70 of the opposing cam brackets 71 secured to the table 18.

Another arm 72 is secured upon the cross shaft 55 to be oscillated when the same is 40 rocked and it will be observed that the said arm is of exactly half the length of the arms 56 for a purpose later to be explained. This arm cooperates with a normally parallel lever arm 73, the latter being connected with 45 the arm 72 through the medium of a link 74. The arm 73 is of a length equivalent to the length of the arms 56, the purpose for which will also be explained later, and the upper end of this arm 73 pivotally joins 50 with a pitman arm 75, the purpose for which will later appear, and the lower end thereof pivotally connects with a link 76, guided by a bracket 77 secured to one of a pair of supporting frames 78, the said link 76 being in turn pivotally joined with a rock 55 lever 80 pivoted at 81 to one of the standards 14 and which is pin and slot connected as at 82 to the table 18.

A rock shaft 83 is mounted upon the table 60 18 having one end thereof bearing in a bracket 84 secured to the table and the other end thereof bearing in the upwardly projecting wall portion 85 of the said table, the wall making provision for an elevated shelf por-

tion 86. A cam arm 87 is fixed upon the rock shaft 83 and is provided with a seat portion 88 adapted to accommodate the lateral fingers 69 of the bracket 68 secured to the saw head 65 when these members are resting in their normal lowered position, see 70 Figure 6, and this cam arm is also provided with an abutment shoulder 89 adapted to be engaged by the said fingers 69 when the saw is being elevated, as indicated in Figure 5. Engagement of the fingers 69 with the abutment shoulder 89 effects a rocking of the shaft 83 and which serves a purpose soon to be described.

The cam arm 87 is also provided with a locking notch 90 adapted to be engaged by a lock dog 91 slidably mounted in a bracket 92 secured to the table 18. The lock dog 91 is pin and slot connected as at 93 to a rocker head 94 pivotally mounted in suitable brackets upon the table 18, as shown, and which is spring held and limited as at 95 to the position shown in Figure 6. This rocker head 94 is provided with a pendent finger 96 which projects downwardly through a slot provided therefor in the table 18. 90

A vertical supporting bracket 97 is secured to the base 1 and supports a rock shaft 98, to one end of which is secured a slotted crank lever 99 which is pin connected as at 100 to the slide 4 of the vertically movable table 3. 95 A crank lever 101 is secured to the opposite end of the cross shaft 98 and the said crank is pivoted to a latch release bar 102 slideable through a head member 103 vertically movable in and guided by a slotted bracket 104 secured to the shelf 17, and is toggle-link connected as at 105 to a cross shaft 106 which has bearings in the bracket 104 and bracket 107 also secured to the bottom of the shelf 17. The opposite end of this cross shaft 106 is provided with a hand lever 108, the purpose for which and the toggle links 105 will later appear. The bar 102 is provided with a heel portion 109 adapted, when the said bar 102 is reciprocated, by reason of upward movement of the slide 4, to engage a crank member 110 pivoted as at 111 to the shelf 17 and which is provided with a forked end 112 adapted to engage the pin 113 of a release dog 114 vertically guided as at 115. It will be readily apparent, by reference to Figure 1 that when the crank 110 is engaged by the heel 109 the release dog 114 will be forced upwardly into engagement with the pendent finger 96 to thereby rock the head 94 to effect release of the lock dog 91. 115

A stop 116 is secured upon the upper face of the shelf 17, the purpose for which will later appear. 125

A small pulley is fixed upon the saw carrying cross shaft 64 and this pulley is rotated to drive the saw 63 through the medium of

a belt 118, which takes over one side of the double pulley 119 loosely mounted upon the cross shaft 67. The pulley 119 is driven by a belt 120 which takes thereover and over one side of a double pulley 121 which is in turn driven by the belt 122 which takes thereover and over the pulley 123 fixed upon the drive shaft of the power motor 52.

In the operation of my machine, the patch 10 stock is automatically fed into the machine in a continuous strip, has an adhesive substance applied thereto while it is being fed into the machine, and is automatically cut to the proper patch lengths in the manner 15 now to be described. For properly feeding the patch stock into the machine, I provide a stationary clutch box 124 in which is pivotally mounted pairs of opposing spring pressed clutch dogs 125 which are also 20 toothed along the patch stock engaging edges thereof and positioned and held in a manner for permitting free passage of the patch stock strip therethrough in one direction only. The clutch box 124 is laterally 25 adjustable as at 126 and is supported upon a bracket 127 secured to the adjacent supporting standards 14. As before stated, this clutch box 124 is stationary and acts, not as a patch stock feeding medium, but as 30 a back check holding device.

For the actual feeding of the patch stock into the machine in the manner and degree necessary, I provide a pair of clutch boxes constructed similarly to the boxes 124 35 and also laterally adjustable as at 126, see Figures 18 and 21. One of these boxes is designated 128 and is secured to the shelf portion 86 of the table 18 as at 129 and moves only when the table moves, in the 40 manner and for the purpose later to be described.

The other clutch box 130, which forms the principal patch stock feeding medium, is 45 slidably mounted along a slide bar 131 secured at 132 to the clutch box 128, and for this purpose is secured thereto a slidable rack bar 133. A rack segment 134 is adapted to cooperate with the slidable rack 133 and the said segment is pivoted at 135 to 50 the wall 85 of the table 18 and is adapted to be oscillated through the medium of the slotted arm 136. The arm 136 is oscillated, by reason of its connection, through the medium of the adjustably connected bar 55 137, to another slotted arm 138 fixed to the end of the rock shaft 83 so as to be oscillated when that shaft is rocked and which is spring connected as at 139 to the wall 85 of the table 18 so as to normally tend to 60 force the clutch box 130 in the direction indicated by the arrow on Figure 2. It will be remembered that this rock shaft 83 is the one upon which the cam arm 87 is mounted and that this shaft 83 is positively rocked under the action of the upward movement of

the soft carriage head 65. The tendency of action of the spring 139 is coincident with that of the action on the abutment 89 as just referred to and the tension of this spring is such as to have a cushioning effect when 70 the fingers 69 return to their normal position indicated in Figure 1.

An adhesive substance applying mechanism 140 is secured to the shelf 86 of the table 18 and this mechanism may be in the 75 nature of a hollow glue containing box provided with a pair of opposing rollers 141 mounted on stub shafts 142 and adapted to pick up the adhesive substance and apply it to the patch stock strip as it is forced 80 through the box.

A laterally movable table 143 is provided and the same includes a slide portion or extension 144 guided as at 145 upon the table 18 and this movable table includes an elevated and laterally projected deck portion 146 corresponding in height to the deck portion 86 of the table 18. The deck 146 is provided with a cut out portion 147 adapted to accommodate a spring pressed plate 90 148 positioned in a manner for receiving and frictionally holding the cut patch length which is to be next inserted into the cut out portion formed by the saw 63. 149 designates an abutment plate secured to the 95 deck 146 to cooperate with the spring pressed plate 148 in holding the stock in the manner just explained, and this plate is in longitudinal alignment with a similar guide plate 150 secured to the projected deck 100 portion 86 of the table 18 by the bridge plate 151.

By reference to Figure 26 it will be observed that the plates 148 and 149 are each corrugated through their length so that 105 they will not scrape the glue from the sides of the patch plug fed into and held therebetween.

A slide member 152 is provided and is adapted to be guided by the adjacent edges 110 of the deck 86 and 146 and this slide plate 152 has fixed thereto a pair of curved inverted V-shaped knives 153 secured to the slide by the bridge and guide plate 154, as shown. A cam head 155 is secured upon the rock shaft 83 and is provided with a cam groove 156. A knife actuated lever 157 is pivoted to a bracket 158 secured to the table deck 86 and the said lever is provided at one end with a downwardly projecting pin 159 adapted to project into and be acted upon by the cam groove 156 and at the other end by a slide engaging detent 160, which is slidable in a recess 161 formed in the end of the lever 157 and which is adapted to be spring pressed outwardly and to be retracted by reason of the action of the link 162 connected thereto and as at 163 to the bracket 158. As the lever 157 is moved by action of the cam 155 in the direction indi- 115 120 125 130

cated by an arrow on Figure 23 the detent 160 will engage the slide 152 and force the same to the cutting position until the link 62 has retracted the said detent to a point 5 where it will no longer exercise its slide engaging function so that the knives may be quickly returned to their normal position by action of the spring clearly shown in Figure 27, so as to be out of the way 10 when the patch stock is again fed past the knives.

The purpose of the movable deck 146 is to receive the patch stock as it is fed, to hold it as it is cut and to transfer the same to a 15 position immediately above the cut out portion formed by the saw 63 in the stock to be patched and to hold the same in such position until it has been driven home in a manner later to be described. For providing 20 this movement of the deck 146 to the position referred to, and in timed relation to just succeed the cutting action of the knives and the removal upward of the saw 63 and immediately preceding the action of 25 the plug inserting mechanism, I provide a cam plate 164 adjustably secured as at 165 to a slide plate 166 guided as at 167 in suitable guides secured to the table 18. Pivotally secured to the cam plate 164 as at 30 168 is a cam plate moving arm 169, the other end of which is connected to the cross shaft 67 so that when the arms 56 are oscillated movement of the cam plate will be effected. The cam plate 164 is provided with a cam 35 groove 170 and which includes a dwell portion 171 to take care of the movement of the cam plate more than necessary to effect the desired moving of the deck 146. An operating lever 172 cooperates with the cam 40 plate in effecting the movement of the deck 146 and this operating lever is adjustably fulcrumed as at 173 upon an overhead bracket 174 secured to the table 18 and the said lever is provided at one end with a pin 45 175 adapted to project into and be acted upon by the cam groove 170 and is provided at its opposite end with a slot connection for engaging the driver pin 176 of the slide 144.

50 Supported in the frames 78 are upper and lower guide rods 177 upon which a plate 178 is slidably guided as at 179. Another plate 180 is secured by connecting brackets 181 to the plate 178 to move therewith in the 55 manner and for the purpose soon to be described. The plate 178 is provided with longitudinal slot 182 in which is adapted to reciprocate a slide block 183 which has a pivotal connection as at 184, with the pitman 75 hereinbefore mentioned, and which is link connected as at 185 to a rock shaft 186 which extends through the said plate 178 and over and through the plate 180 where the said shaft is again link connected as at 60 187 to a rocking lever 188 adjustably piv-

oted as at 189 to the plate 180 and which is provided with a double bifurcated end 190 adapted to engage a cross pin 191 through a plunger shaft 192 vertically movable in brackets 193 secured to the said plate 180. 70 This plunger shaft 192 is provided at its lower end with a guide head 194 in which is adjustably secured as at 195 the patch driving plunger head 196.

The plates 178 and 180 are adapted to be 75 moved, through the medium of the pitman connection 75 with the levers hereinbefore referred to, forwardly to a position where the plunger head 196 will be positioned directly over the patch which it is adapted 80 to drive home. Mechanism is provided whereby a portion of the movement of the pitman 85 will be utilized to longitudinally move the plates 178 and 180 and the plunger, which the latter plate carries, and a small 85 degree of continued movement of this pitman is utilized to vertically move said plunger to effect the actual driving home of the plunger, the said mechanism being such that this vertical movement of the 90 plunger is effected without further longitudinal movement of the parts mentioned.

To effect the above mentioned movements, I provide block stop detent 197 which is guided and abutted as at 198 and which is pivoted as at 199 to a detent release link 200 which is in turn pivoted at 201 to the plate 178, as shown. The other end of the link is pivoted to a releasing bar 202 which is also linked at 203 to the plate 178. This 100 bar 202 has an abutting head 204 adapted to engage with a stop 205 secured to the table 18 just before the plates 178-180 have been moved to the point desired. By reference to Figure 11 it will be noticed that 105 as the abutment 204 engages the stop 205, the parts just described will be actuated, as indicated in the dot and dash lines in that figure to effect a release of the detent 197 and thereby permit movement of the block 110 183 free of the plate 178 so that the said movement may properly act upon the links, shaft and lever hereinbefore described in a manner for effecting the downward movement of the plunger 196. A stop abutment 115 206 is secured to the plate 178 in position for being engaged by the rear end of the releasing bar 202 so that when the parts are positioned, as indicated in dot and dash lines on Figure 11, a positive stop of the 120 plates 178 and 180 will be effected, and a spring 207 is interposed between the abutment 206 and the link 200 so as to normally force the detent 197 to the locked position indicated in Figure 1.

An arched bracket 208 is secured upon the top face of the standard 2 in the position indicated in full lines on Figure 3 and in dotted lines on Figure 2. This bracket 125 serves to provide suitable guides for a verti- 130

cally movable rod 209 which includes, at the lower end thereof, a work presser foot 210 and which is adapted to be forced downwardly to the position illustrated in Figure 4 by a spring 211. It will be observed that the work presser foot 210 normally rests at a position below the cutting edge of the saw 63 and at a point in advance of the saw, and its relation with the saw and the vertically movable table 3 is such that when the table is moved upwardly to the operative position, the said foot will engage the work and hold it tightly to its position upon the table while the defect is being removed by the saw 63.

A bracket 212 is adjustably secured to the end saw head 65 adjacent the saw blade 63 and this bracket serves to form a supporting medium for the guide bracket 213 which is pivoted thereto as at 214, and which is provided with an extended portion 215 adapted to project over a portion of the bracket 213, as shown in Figures 4 and 9. This extension 215 is slotted to permit the passing therethrough of an adjustment screw including an abutment head, and the said screw cooperates with a spring in forming a spring pressed and limited connection between the bracket extension 215 and the bracket 212, as indicated at 216. The vertically movable rod is guided by the bracket 214 and a spring 218 cooperates with the bracket and the rod to force the latter normally downward to the position indicated in full lines in Figure 9, and in a manner for forming a yieldable connection which will yield under the upward pressure of the stock to be patched in the manner indicated in the dot and dash lines on Figure 9. A wooden chip breaker 219 is secured to the bottom end of the rod 217 and is adapted to engage the stock to be patched in a manner for preventing the said stock from chipping under action of the saw while the same is effecting its cut, as illustrated in dot and dash lines in Figure 9, from which it will also be observed that the breaker head 219 is provided with a suitable slotway to permit it to straddle the saw so as to more readily effect its function. By reference to Figure 10, it will be readily seen that the construction and manner of mounting of this chip breaker mechanism is such that when the saw 63 is effecting a long cut, as indicated by dot and dash lines in that figure the said mechanism may yield and take the position illustrated in the said Figure 10.

The rock cam 87 is provided with a slot 220 for accommodating a link 221 pivoted at one end of that cam and at the other end to a table locking lever 222 which is in turn pivoted at 223 to the bottom face of the table 18 and which has its other end bifur-

cated to straddle a cross pin 225 on the lock detent 226 which is guided at 227 upon an abutment 228 secured to the table 18 which is adapted to enter, at times, one or the other of a pair of lock notches 229 formed in the shelf 17 to lock the table 70 against backward movement for a purpose later to be described.

As diagrammatically illustrated in Figure 19 upper and lower guides 230 of key steel may be provided, if desired, to aid in the guiding of the patch stock through the feeding boxes.

Operation.

In the operation of my invention, assuming the parts to be at rest, as indicated in Figure 1, the operator first places the stock to be patched upon the table 2 with the pitch pocket, see for example Figures 9 and 12, to be patched positioned directly beneath the defect removing saw 63. He then presses down the foot lever 9, releasing its connection with the cam 11 and allowing the weighted lever to gravitate in the direction of the arrow on Figure 1 and thus causing the toggle levers to straighten and to force the table 3 to its elevated position illustrated in dot and dash lines on said Figure 17. As the stock rises, it is engaged and spring held by the members 210 and 219 and the cutting out of the pitch pocket is effected, as indicated in Figures 13, 16 and 17. Simultaneously with the lifting of the slide 4 and the table 3, the lever 99 is actuated which causes, through lever 102, upward movement of the release dog 114, by reason of which the lock dog 91 is released from engagement with the cam 87. Simultaneously with this action just explained, the toggles 39 have been broken, as indicated in Figure 17 and the clutch dogs 31 permitted to grip and lock with the master block 25, which is being driven through the medium of the crank disk 27 and pitman 26, thus causing the arms 56 to be rocked forwardly and, by reason of the arms 66, effecting an upward lifting of the saw head 65 guided by the cam grooves 70 and causing a rocking of the shaft 83 through approximately one-sixth of a revolution. The saw having effected its defect removing function is thus lifted out of the way of other mechanism. The rocking of the shaft 83 effects, through the lever connections 136-138 with the segment 134 and its cooperating rack, a forward movement of the clutch box 130 of about three and a half to four inches, so that when the saw carriage returns to its normal position guided down the grooves 70, and the box 130 returns to its normal position by reason of the reversal of the action just explained, the patch stock strip will be fed into the machine a distance

equivalent to the distance the clutch box has moved forwardly.

Simultaneously with the movement of the saw carriage, forward movement of the cam plate 184 is effected through the pitman arm 169, thus giving lateral movement of the deck 146 by reason of the operating lever connection 172 therewith and with the said deck, to effect the proper transferring of 10 the patch block held by the said deck to a position immediately above the saw kerf formed in removing the defect. It will be noticed that the start of the cam groove 170 includes a short dwell portion sufficient to 15 permit the saw 63 to carry up a sufficient distance to clear the deck preceding its full movement to the transfer position.

Simultaneously with the movement of the deck 146, the plates 178 and 180 are being 20 moved by reason of the pitman arm connection 75 therewith and with the arms 73 and 72. It will be observed that the arms 73 being of a length equivalent to the arms 56 and the same being, at the adjustment 25 now being described, fixedly pivoted at its lower end, the movement of this arm will be the same as the movement of the said arm 56, this being true in all cases where a short patch is being applied. By reason 30 of the locked condition of the detent 197, the pitman 75 carries the said plates forwardly until the plunger head 196 is almost directly over the saw kerf at which point the stop 205 will be engaged and a release 35 of the detent 197 effected, whereupon further forward movement of the plates will cease and the continued forward motion of the pitman 75 will cause plunger action on the plunger rod 192 and head 196 to effect the 40 driving home of the patch plug from its frictionally held position in the outer end of the deck 146, see Figures 1, 5 and 11.

On the return rock of the arms 56—57, the saw head 65 will be returned to its normal 45 position, the rock shaft 83 rocked back to its normal position and locked by the dog 91, the saw carriage being cushioned by the spring 139 on its return action, and by reason of the dog 62 engaging the toe 45 50 and rocking the shaft 80, as indicated in Figure 17, the table 3 will be again lowered to its normal position and the clutch dogs 31 released and the parts again set at rest, with the exception of the driving transmissions, as shown in Figure 1.

The foregoing description has all related to the operation of the machine for applying a short patch, that is a patch of approximately three and a half inches in length. 60 It should be observed that in this form, the brackets 20—21 abutting, no movement of the table 18 rearwardly is permitted, and the position of the lever 80 and link 76 being relatively stationary, the arm 73 func-

tions exactly as though it were fixedly pivoted at its inner end. The function of these parts is slightly modified in the application of a long patch, as will presently appear.

When it is desired to cut out defects longer in length than will be readily covered by the short or three and a half inch patch, it being understood that these defects or patch pockets very infrequently exceed a length such as would not be effectively cured by a five and a half inch patch, mechanism is provided in the machine for adjusting the machine for applying such a long patch in the same effective manner as a short patch is applied.

When the operator desires to apply such a long patch, it is only necessary for him to move the hand lever 108 slightly forwardly so as to manipulate the toggle links 105 to effect the adjustment of the arms 102 to the position illustrated in Figures 6 and 8, from which it will be readily observed that the heel portion 9 thereof will be positioned in a manner for freely passing the crank member 110 without engaging the same with the resultant immediate release of the lock dog 91. With the parts in this adjusted position, when the table 3 is lifted to elevate the stock to be patched into engagement with the defect cutting saw 63, the upward movement of the slide 4 will not effect a releasing of the lock dog 91 for reasons above described, and the cam 87 thus remaining locked against movement such as will permit the saw carriage 65 to ride upward guided by the guide groove 70, the table 18 will be caused to move forwardly two inches, as is illustrated in Figure 8, by the dot and dash lines, this movement being effected directly through the crank arms 56 and the saw carriage carrying arms 66 acting through the fingers 69 directly against the abutment 89. The table is limited to two inches of movement, the two inches additional movement necessary to effect the additional cut of the saw to make a five and a half inch cut, see Figures 8, 10 and 16, by the stop 116 which engages the finger 96 after it has passed freely over the release dog 114, as is indicated by dot and dash lines on the said Figure 8. It should be understood that the clutch box 128 being fixed to the table moves therewith, this being the only time that this box does move, and is thus caused to slip along the patch stock strip a distance of two inches.

By reason of the fact that three and a half inches of the patch stock strip is already in position to be held by the deck 146 while and after being cut by the knives 153, see Figure 23, this two inch movement of the table, which, of course, carries the deck 146 and all the cooperating mechanism with it, effects a sliding of the plug holding ele-

ments of the deck and the cooperative mechanism referred to along the strip a distance of two inches so that the five and a half inches of stock necessary for the long 5 patch will be cut when the knives are actuated. The patch stock strip is, of course, held from movement with the main table 18 and the mechanisms carried thereby, by reason of the action thereupon by the clutch 10 box 124 secured to the stationary framing of the machine as at 127.

When the table 18 is returned to its normal position, the clutch box 128 effects a corresponding feed of the patch stock strip 15 so that the same will be in normal relation with the knives and deck 146 for the next operation whether it be a three and a half inch patch that is to be made or a five and a half inches patch.

20 From the above description, it should be clear how the five and a half inch cut is made and how the five and a half inch patch plug is fed, it being cut in the same manner that the short patch is cut. In this adjustment of the machine, it is necessary, of course, to cause the plates 178 and 180 and the plunger head 195 carried thereby to travel the additional two inches made necessary by movement of the table. By reference to Figure 8, it will be readily understood how this is possible. The two inches of forward movement of the table 18 causes the rock lever 80 to rock, as is indicated by the dot and dash lines on that figure and, 25 by reason of thus moving the lower pivot of the lever 73 rearwardly and the action against the center pivot of this lever exerted by the half-length arm 72 and the link 74, the upper end of this lever 73 and which acts upon the pitman 75 which drives the plates 178 and 180 as before described, will be compounded so that the two inches of movement of the table 18 or rather the initial two inches of movement of the arms 56 30 will effect a four inch movement of the pitman 75 and the plates locked thereto by the 35 detent 197.

The remainder of the mechanisms of the machine functioning exactly as they do in applying the three and a half inch patch, 40 further description of the operation is deemed unnecessary.

By reference to Figure 22 it will be observed that the bracket 68 is vertically adjustably secured to the saw carriage 65. By thus adjusting the relative position of the bracket 68, the relation of the saw 63 with the stock to be patched may be slightly varied by taking up wear of the saw, so that 45 the groove cut thereby will always be perfectly accurate.

It will be observed from Figures 23 and 50 30 that as the knives cut the patch plug from the patch stock strip there is a slight degree of waste, due to the small piece cut

out, and thus making it necessary to feed into the machine at each interval, an equivalent excess of patch stock so that the patch plug cut will exactly match the cut made by the saw. By reason of the adjustable 70 connection between the slotted arms 136 and 138 by the rod 137 accurate adjustment of these parts is readily effected for ensuring absolute accuracy of the patch stock feed.

It will also be observed that the movement 75 of the chipper head 219 into the saw 63 is adjustably limited as at 216 to prevent the same from going too far into the said saw.

The relation of the lock dog 91 with the lock notch 90 of the cam 87 is also adjustably limited in a manner whereby perfect adjustment may be effected as at 95.

The clutch boxes are all laterally adjustable as at 126 and the plunger head 196 is correspondingly laterally adjustable in the 80 retaining head 194, as illustrated in Figure 29.

It will also be observed that the members 188 and 172 are adjustably fulcrumed at 85 189 and 173 so that absolute accuracy of movement of the parts effected by these members is ensured.

While in the illustration made, lock notches 229 are provided for both the stationary position of the table 18 and the two inch forwardly moved position of the table, it should be understood that cooperation of the lock detent 226 therewith is only necessary in case of applying the long patch so that backward movement of the table 18, before the saw carriage has been brought back to its normal position, is made impossible, see Figure 6.

In Figure 25 is illustrated a slight modification of the invention and in this figure 100 the abutment plate 149 of the deck 146 is provided with an upward and laterally bevelled projection 231 adapted to lap over the patch stock strip 233 at the end thereof which is adapted to be cut off to form the patch plug and in a manner whereby any tendency of the said end to rise as it is being cut is overcome. As above stated, this projection is bevelled and, when such construction is utilized, the fore end of the plunger head 96 is also bevelled as at 232 to cooperate therewith so that the said head may engage as nearly as possible the entire length of the patch plug.

From the foregoing description taken in connection with the accompanying drawings, it is thought that the novel details of construction, the operation and advantages of my invention will be readily apparent to those skilled in the art to which it appertains.

What I claim is:

1. In a machine for patching pitch pockets, a recess cutting element for cutting and removing the pitch pockets out of the same 130

- surface of the stock to be patched, thus providing a recess in the surface only of said stock, means for fixing a patch into the recess formed by the cutting element in re-
5 moving the pitch pocket, and means for operating the cutting element and the patch fixing means.
2. In a machine for patching pitch pock-
ets, a recess cutting element for cutting and
10 removing the pitch pockets out of the same
surface of the stock to be patched, thus
providing a recess in the surface only of
said stock, means for fixing a patch into the
recess formed by the cutting element in re-
15 moving the pitch pocket, means for operat-
ing the cutting element and the patch fixing
means, and means for supporting the stock
to be patched in a freely movable manner
before cutting and patching, and means for
20 tightly holding the said stock during the
cutting and patching thereof.
3. In a machine for patching pitch pock-
ets, a recess cutting element for cutting and
removing the pitch pockets out of the same
25 surface of the stock to be patched, thus pro-
viding a recess in the surface only of said
stock, means for fixing a patch into the
recess formed by the cutting element in re-
moving the pitch pocket, means for operat-
30 ing the cutting element and the patch fixing
means, means for adjusting the stroke of the
cutting element, and means for adjusting
the position of the patch fixing means to
adapt the machine for applying abnormal
35 sized patches.
4. In a machine for patching pitch pock-
ets, a recess cutting element for cutting and
removing the pitch pockets out of the same
surface of the stock to be patched, thus
40 providing a recess in the surface only of
said stock, means for fixing a patch into the
recess formed by the cutting element in re-
moving the pitch pocket, means for operat-
45 ing the cutting element and the patch fixing
means, means for automatically feed-
ing a continuous strip of patch stock
into the machine in accordance with its
needs, and means for cutting off the desired
50 patch length from the strip to form the
patch.
5. In a machine for patching pitch pock-
ets, a recess cutting element for cutting the
pitch pockets out of the surface of the stock
to be patched, means for fixing a patch into
55 the recess formed by the cutting element in
removing the pitch pocket, means for operat-
ing the cutting element and the patch fix-
ing means, means for adjusting the stroke
of the cutting element, means for adjust-
60 ing the position of the patch fixing means to
adapt the machine for applying abnormal
sized patches, and means for automatically
feeding a continuous strip of patch stock
into the machine at intervals and in de-
65 gree equivalent to its needs as determined

by the adjustment of the cutting element
stroke and patch fixing means position, and
means for cutting the desired patches from
the strip in lengths corresponding to the
degree fed and the defect removed.

6. In a machine for patching pitch pock-
ets, a recess cutting element for cutting and
removing the pitch pockets out of the same
surface of the stock to be patched, thus pro-
viding a recess in the surface only of said
70 stock, means for fixing a patch into the
recess formed by the cutting element in re-
moving the pitch pocket, means for operat-
ing the cutting element and the patch fixing
means, means for supporting the stock to be
75 patched in a freely movable manner before
cutting and patching, means for tightly
holding the said stock during the cutting
and patching thereof, means for automatically
feeding a continuous strip of patching
80 stock into the machine in accordance with
its needs, and means for cutting off the de-
sired patch length from the strip to form
the patch.

7. A machine of the class described com-
prising a recess cutting element for cutting
and removing the defects from the same
surface of the stock to be patched, thus pro-
viding a recess in the surface only of said
90 stock, means for feeding the stock to be
patched to the cutting element, means for
feeding patching stock into the machine,
means for applying an adhesive substance
to the patching stock while being fed, means
95 for severing the patching stock in units of
length equivalent to the recess formed by
the cutting element in removing the defects,
and means for inserting the patch into the
said recess.

8. A machine of the class described, com-
prising a recess cutting element for cutting
and removing the defects from the same sur-
face of the stock to be patched, thus pro-
viding a recess in the surface only of said
100 stock, means for feeding the stock to be
patched to the cutting element, means for
feeding patching stock into the machine,
means for applying an adhesive substance to
the patching stock while being fed, means
105 for severing the patching stock in units of
length equivalent to the recess formed by the
cutting element in removing the defects, and
means for inserting the patch into the said
recess.

9. A machine of the class described com-
prising a recess cutting element for cutting
and removing the defects from the same
surface of the stock to be patched, thus pro-
viding a recess in the surface only of said
120 stock, means for feeding the stock to be
patched to the cutting element, means for re-
moving the cutting element from cutting re-
lation with the stock to be patched, means
for feeding patching stock into the machine,
means for applying adhesive substance to
125

the patching stock while being fed, means for severing the patching stock in units of length equivalent to the recess formed by the cutting element in removing the defect, and 5 means for inserting the patch into the said recess.

10. A machine of the class described comprising a recess cutting element for cutting and removing the defects from the same surface of the stock to be patched thus providing a recess in the surface only of said stock, means for feeding the stock to be patched to the cutting element, means for lifting the cutting element upwardly out of cutting relation with the stock to be patched and out of the way of the other mechanisms of the machine, means for feeding patching stock into the machine, means for applying an adhesive substance to the patching stock 15 while being fed, means for severing the patching stock in units of length equivalent to the recess formed by the cutting element in removing the defect, and means for inserting the patch into the said recess.

20. 11. A machine of the class described comprising a recess cutting element for cutting and removing the defects from the same surface of the stock to be patched, thus providing a recess in the surface only of said stock, means for feeding the stock to be patched to the cutting element, means for lifting the cutting element upwardly out of cutting relation with the stock to be patched and out of the way of the other mechanisms of the machine, means for feeding patching stock into the machine, means for applying an adhesive substance to the patching stock while being fed, means for severing the patching stock in units of length equivalent 25 to the recess formed by the cutting element in removing the defect, means for holding each severed length of patching stock in position for and while being forced into the recess formed by the cutting element, and 30 means for forcing the said patching stock length into the said recess.

12. A machine of the class described comprising a recess cutting element adapted to remove defects from the face of the stock to be patched, means for feeding the stock to be patched to the cutting element, means for lifting the cutting element upwardly out of cutting relation with the stock to be patched and out of the way of the other mechanisms of the machine, means for feeding patching stock into the machine, means for applying an adhesive substance to the patching stock while being fed, means for severing the patching stock in units of length equivalent to the recess formed by the cutting element, means for transferring each cut length of patching stock from its cut position to a position above the recess formed by the cutting element in removing 35

the defect, and means for forcing the said 65 patching stock length into the said recess.

13. A machine of the class described comprising a recess cutting element adapted to remove defects from the face of the stock to be patched, means for feeding the stock 70 to be patched to the cutting element, means for lifting the cutting element upwardly out of cutting relation with the stock to be patched and out of the way of the other mechanisms of the machine, means for feeding patching stock into the machine, means for applying an adhesive substance to the patching stock while being fed, means for severing the patching stock in units of length 75 equivalent to the recess formed by the cutting element, means for transferring each cut length of patching stock from its cut position to a position above the recess formed by the cutting element in removing the defect, means for forcing the said patching stock length into the said recess, and means whereby the machine may be adjusted to remove defects and to apply patches of different dimensions.

14. A machine of the class described comprising a recess cutting element adapted to remove defects from the stock to be patched, means for feeding the stock to be patched to the cutting element, means for lifting the cutting element upwardly out of cutting relation with the stock to be patched, means actuated by the upward movement of the cutting element for feeding patching stock into the machine, means for severing the patching stock into units of length equivalent to the recess formed by the cutting element in removing the defect, and means for inserting the patch into the recess.

15. A machine of the class described comprising a recess cutting element, means for feeding the stock to be patched to the cutting element, means for lifting the cutting element upwardly out of cutting relation with the stock to be patched, means actuated by the upward movement of the cutting element for effecting a feeding of patching stock into the machine at intervals and in degree according to the length of the recess formed by the cutting element, means for severing a patch length from the patching stock, the said severing means being positioned relative to the stock feeding means to cause a severing of a patch length equivalent to the length of the recess formed by the cutting element, and means for inserting the patch length into the recess.

16. A machine of the class described comprising a recess cutting element, means for feeding the stock to be patched to the cutting element, means for lifting the cutting element upwardly out of cutting relation with the stock to be patched, means actuated by the upward movement of the cutting

- element for effecting a feeding of patching stock into the machine at intervals and in degree according to the length of the recess formed by the cutting element, means for 65
 5 severing a patch length from the patching stock, the said severing means being positioned relative to the stock feeding means to cause a severing of a patch length equivalent to the length of the recess formed by
 10 the cutting element, means for causing the recess cutting element to cut an abnormal length recess and for moving the severing means corresponding for severing an abnormal length patch, and means for inserting
 15 the patch length into the recess.
17. A machine of the class described comprising a recess cutting element, means for feeding the stock to be patched to the cutting element, means for lifting the cutting element upwardly out of cutting relation with the stock to be patched, means actuated by the upward movement of the cutting element for effecting a feeding of patching stock into the machine at intervals and in degree according to the length of the recess formed by the cutting element, means for severing a patch length from the patching stock, the said severing means being positioned relative to the stock feeding means to cause a severing of a patch length equivalent to the length of the recess formed by the cutting element, means for inserting the patch length into the recess, and means thrown into action by the foot released and weight operated means for automatically operating the elements and means stated through a single cycle of operation.
18. A machine of the class described comprising a recess cutting element, means for feeding the stock to be patched to the cutting element, means for lifting the cutting element upwardly out of cutting relation with the stock to be patched, means actuated by the upward movement of the cutting element for effecting a feeding of patching stock into the machine at intervals and in degree according to the length of the recess formed by the cutting element, means for severing a patch length from the patching stock, the said severing means being positioned relative to the stock feeding means to cause a severing of a patch length equivalent to the length of the recess formed by the cutting element, and means for transferring each severed length of patching stock from its severed position to a position above the recess and for holding the same in position for and while being forced into the recess, and means for inserting the patch length into the recess.
19. A machine of the class described comprising a recess cutting element for cutting and removing the defects from the same surface of the stock to be patched, foot released weight operated means for moving the stock to be patched to operative relation with the said element, means for applying a patch to and securing the same into the recess formed in removing the defect, and means also thrown into action by the foot release and weight action for automatically operating the defect removing element and patch applying means through a single cycle of operation.
20. A machine of the class described comprising a recess cutting element, foot released and weight operated means for moving the stock to be patched to operative relation with the cutting element, means for feeding the stock to be patched to the cutting element, means for lifting the cutting element upwardly out of cutting relation with the stock to be patched, means actuated by the upward movement of the cutting element for effecting a feeding of patching stock into the machine at intervals and in degree according to the length of the recess formed by the cutting element, means for severing a patch length from the patching stock, the said severing means being positioned relative to the stock feeding means to cause a severing of a patch length equivalent to the length of the recess formed by the cutting element, means for inserting the patch length into the recess, and means thrown into action by the foot released and weight operated means for automatically operating the elements and means stated through a single cycle of operation.
21. A machine of the class described comprising a recess cutting element for cutting and removing the defects from the same surface of the stock to be patched, thus providing a recess in the surface only of said stock, means for fixing a patch into the recess formed by removing the defect, means for operating the cutting means and the patching means, said last named means including constantly moving power applying devices, and means whereby the said devices are caused to effect functioning of the machine through a single cycle of operation.
22. A machine of the class described comprising a base, a table supporting standard mounted upon the base, a table vertically slidable upon said standard, a rotary saw cooperative with said table for cutting and removing defects from surface of the stock to be patched, means for rotating said saw, foot released weight actuated means for elevating the table into cooperative relation with the saw, means for feeding a patch stock strip into the machine, means for severing the strip into predetermined lengths, means for transferring the severed lengths of patch stock from the point at which they are severed to a point just above the recess formed by the saw in removing the defect, means for elevating the saw out of the cut,

and before the transfer of the patch plug, means for forcing the patch plug into the said recess, and means operating the various mechanisms.

23. A machine of the class described comprising a base, a table supporting standard mounted upon the base, a table vertically slidable upon said standard, foot released weight actuated means for elevating the table, a rotary saw cooperative with the table in removing the defects from the stock to be patched, means for rotating said saw, yieldable means adapted to engage the stock to be patched when the table is elevated to hold the same to position, means for feeding a patch strip into the machine, means for severing the strip into predetermined lengths, means for elevating the saw out of the cut, means for transferring the severed lengths of patch stock from the point at which they are severed to a point just above recess formed by the saw in removing the defect, means for forcing the patch plug into the said recess, and means for operating the various mechanisms through a single cycle of operation.

24. A machine of the class described comprising a base, a table supporting standard mounted upon the base, a table vertically slidable upon said standard, foot released weight actuated means for elevating the table, a rotary saw cooperative with the table in removing defects from the stock to be patched, means for rotating said saw, yieldable means adapted to engage the stock to be patched when the table is elevated to hold the same to position, clutch boxes adapted to feed a patch stock strip into the machine, means for holding one clutch box stationary while another is moved to effect a feeding of the said strip in one direction only, means for severing the strip into predetermined lengths, means for elevating the saw out of the cut, means for transferring the severed lengths of patch stock from the point at which they are severed to a point just above the recess formed by the saw in removing the defect, means for forcing the patch plug into the said recess, and means for operating the various mechanisms through a single cycle of operation.

25. A machine of the class described comprising a base, a table supporting standard mounted upon the base, a table vertically slidable upon said standard, foot released weight actuated means for elevating the table, a rotary saw cooperative with the table, in removing defects from the stock to be patched, means for rotating said saw, yieldable means adapted to engage the stock to be patched when the table is elevated to hold the same to position, clutch boxes adapted to feed a patch stock strip into the machine and including a single stationary clutch box, a movable clutch box, and a second clutch

second clutch box movable at times, means for moving the movable clutch box for feeding a short patch, and means for moving the second movable clutch box for cooperating with the other movable clutch box in feeding a long patch, means for severing the strip into predetermined lengths, means for elevating the saw out of the cut, means for transferring the severed lengths of patch stock from the point at which they are severed to a point just above recess formed by the saw in removing the defect, means for forcing the patch plug into the said recess, and means for operating the various mechanisms through a single cycle of operation.

26. A machine of the class described comprising means for removing defects of varied lengths from the face of the stock to be patched, clutch boxes for feeding a patch-stock strip into the machine, means for severing patch lengths from the patch-stock strip, means for applying the patch into the recess formed by removing the defect, and means for altering the relative positions of clutch boxes and severing means to effect severing of varied patch lengths.

27. A machine of the class described comprising recess forming means for removing defects from the stock to be patched, means for applying a patch to and securing the same into the recess, clutch boxes adapted to feed a patch stock strip into the machine and including a single stationary clutch box, a movable clutch box, and a second clutch box movable at times, means for moving the movable clutch box for feeding a short patch, and means for moving the second movable clutch box for cooperating with the other movable clutch box in feeding a long patch, and means for operating the defect removing and the patch applying and securing means.

28. A machine of the class described comprising a base, a table supporting standard mounted upon the base, a table vertically slidable upon said standard, foot released weight actuated means for elevating the table, the said means including toggle links adapted to momentarily lock the table at its elevated position, a rotary saw cooperative with the table in removing the defects from the stock to be patched, means for rotating said saw, yieldable means adapted to engage the stock to be patched when the table is elevated to hold the same to position, means for feeding a patch strip into the machine, means for severing the strip into predetermined lengths, means for elevating the saw out of the cut, means for transferring the several lengths of patch stock from the point at which they are severed to a point just above the recess formed by the saw in removing the defect, means for forcing the patch plug into the said recess and means

for operating the various mechanisms through a single cycle of operation.

29. A machine of the class described comprising a base, a table supporting standard 5 mounted upon the base, a table vertically slidable upon said standard, foot released weight actuated means for elevating the table, a rotary saw cooperative with the table in removing the defects from the stock 10 to be patched, means for rotating the saw, yieldable means adapted to engage the stock to be patched when the table is elevated to hold the same to position, means for feeding a patch strip into the machine, means for 15 severing the strip into predetermined lengths, means for elevating the saw out of the cut, means for transferring the severed lengths of patch stock from the point at which they are severed to a point just above 20 the recess formed by the saw in removing the defect, a plunger for driving the patch plug into the recess formed by the saw in the stock to be patched, and means for moving the plunger to position over the said 25 plug and for forcing the same downward.

30. A machine of the class described comprising a base, a table supporting standard mounted upon the base, a table vertically slidable upon said standard, foot released 30 weight actuated means for elevating the table, a rotary saw cooperative with the table in removing the defects from the stock to be patched, means for rotating the saw, yieldable means adapted to engage the stock 35 to be patched when the table is elevated to hold the same to position, means for feeding a patch strip into the machine, means for severing the strip into predetermined lengths, means for elevating the saw out of 40 the cut, means for transferring the cut lengths of patch stock from the point at which they are cut to a point just above the recess formed by the saw in removing the defect, a plunger for forcing the patch plug 45 into the said recess slidable plates which carry the plunger, a pitman adapted to slide the plates through a part of its travel, a lock detent for locking the plates to move with the pitman, means for releasing the detent to permit the pitman to move further, and connections between the pitman and the plunger whereby the latter is forced downward by the continued movement of the pitman.

50 31. A machine of the class described comprising a recess cutting element, means for feeding the stock to be patched to the cutting element, means for lifting the cutting element upwardly out of cutting relation with the stock to be patched, means for 55 feeding patching stock into the machine at intervals and in degree equivalent to the length of the patch to be made, means for applying an adhesive substance to the patching stock as it is being fed, means for sever-

ing the patching stock into units of length equivalent to the recess formed by the cutting element, means for holding each severed length of patching stock in position for and while being forced into the recess 70 formed by the cutting element, the said holding means including longitudinally corrugated portions for engaging each cut patch length after it has had adhesive substance applied thereto, and means for forcing the said patching stock into said recess. 75

32. A machine of the class described comprising a recess cutting element, a chip breaker pivotally and yieldably mounted in cooperative relation with the cutting element and the stock to be patched, means for feeding the stock to be patched to the cutting element, means for lifting the cutting element upwardly out of cutting relation with the stock to be patched, means 80 actuated by the upward movement of the cutting element for feeding patching stock into the machine by units of length equivalent to the recess formed by the cutting element, means for severing the patching 85 stock, and means for inserting the patch into the recess.

33. A machine of the class described comprising a recess cutting element, a chip breaker spring pressed downwardly, pivotally movable in one direction only and having a bifurcated head for straddling the cutting element, means for feeding the stock to be patched to the cutting element, means for lifting the cutting element upwardly 100 out of cutting relation with the stock to be patched, means actuated by the upward movement of the cutting element for feeding patching stock into the machine by units of length equivalent to the recess 105 formed by the cutting element, means for severing the patching stock, and means for inserting the patch into the recess.

34. A machine of the class described comprising a base, a table supporting standard 110 mounted upon the base, a stock supporting table vertically movable upon said standard, a main table supported above the base, a rock shaft having bearings on said main table, a cam groove guideway mounted upon the main table, a rotary saw, a carriage for the saw, means for rotating the saw, means for elevating the stock supporting table to cause the saw to cut out the defect in the stock to be patched supported thereon, means for moving the saw carriage forwardly upward guided by the cam groove guideway, a rocker cam arm fixed on the rock shaft and adapted to be rocked by the upward movement of the saw, clutch boxes 115 adapted to feed a patch stock strip into the machine including a single stationary clutch box and a movable clutch box, a crank on the rock shaft, means operated by said crank on the rocking of the shaft for mov- 120 125 130

- ing the movable clutch box in one direction on the up movement of the saw carriage and in an opposite direction on the lower-
ing movement of the saw carriage for effect-
ing a feeding of the patch stock strip, means
for cutting off a predetermined length of
the said strip, and means for inserting the
same into the recess formed by the saw.
35. A machine of the class described com-
prising a base, a table supporting standard
mounted upon the base, a stock supporting
table vertically movable upon said stand-
ard, a main table supported above the base,
a rock shaft having bearings on said main
table, a cam groove guideway mounted upon
the main table, a rotary saw, a carriage for
the saw, a vertically adjustable bracket fixed
to the saw carriage and adapted to engage
the guideway, means for rotating the saw,
means for elevating the stock supporting
table to cause the saw to cut out the defect
in the stock to be patched supported there-
on, means for moving the saw carriage for-
wardly upward guided by the cam groove
guideway, a rocker cam arm fixed on the
rock shaft and adapted to be rocked by the
upward movement of the saw, clutch boxes
adapted to feed a patch stock strip into the
machine including a single stationary clutch
box and a movable clutch box, a crank on
the rock shaft, means operated by said
crank on the rocking of the shaft for moving
the movable clutch box in one direction
on the up movement of the saw carriage
and in an opposite direction on the lower-
ing movement of the saw carriage for effect-
ing a feeding of the patch stock strip, means
for cutting off a predetermined length of
the said strip, and means for inserting the
same into the recess formed by the saw.
36. A machine of the class described com-
prising a base, a table supporting standard
mounted upon the base, a stock supporting
table vertically movable upon said standard,
a main table movably supported above the
base, means for moving the table forward
to effect a cutting out of a long defect, a
rock shaft having bearings on said main
table, a cam groove guideway mounted upon
the main table, a rotary saw, a carriage
for the saw, means for rotating the saw,
means for elevating the stock supporting
table to cause the saw to cut out the defect
in the stock to be patched supported there-
on, means for moving the saw carriage for-
wardly upward guided by the cam groove
guideway, a rocker cam arm fixed on the
rock shaft and adapted to be rocked by the
upward movement of the saw, clutch
boxes adapted to feed a patch stock strip
into the machine and including a single
stationary clutch box, a movable clutch box,
and a second clutch box movable at times,
means for moving the movable clutch box
for feeding a short patch, and means for 65
moving the second movable clutch box for
cooperating with the other movable clutch
box in feeding a long patch.
37. In a patching machine, a support for
the stock to be patched, a saw for cutting
out the defect, a patching stock feeder, a
patching stock cutter, a glue applying de-
vice, a patch inserting tool, and means for
effecting the cooperative action of the afore-
said saw, patching stock feeder, patching 70
stock cutter, glue applying device and patch
inserting tool.
38. In a patching machine, a support for
the stock to be patched, a saw for cutting
out the defect, a patching stock feeder, a 80
patching stock cutter, a glue applying de-
vice, a patch inserting tool, means for ef-
fecting the cooperative action of the afore-
said saw, patching stock feeder, patching
stock cutter, glue applying device and patch 85
inserting tool in successive cycles, and
means to arrest action between successive
cycles.
39. A machine of the class described com-
prising a recess cutting element, means for
feeding the stock to be patched to the cut-
ting element, means for removing the cut-
ting element out of cutting relation with
the stock to be patched and out of the way
of the other mechanisms of the machine, 90
means for feeding patching stock into the
machine, means for applying an adhesive
substance to the patching stock, means for
severing the patching stock in units of
length equivalent to the recess formed by 100
the cutting element, and means for insert-
ing the patch into the said recess.
40. A machine of the class described com-
prising a recess cutting element, means for
whereby the cutting element is caused to 105
remove a defect from the stock to be
patched, means for feeding patch stock into
the machine, means for severing the patch
stock into predetermined lengths to form
patch plugs, means for forcing a patch plug 110
into the recess formed by the cutting ele-
ment, and means for moving the said forcing
means to a position in alignment with
the said removed portion and for effect-
ing the forcing action thereof.
41. A machine of the class described com-
prising a recess cutting element, means
whereby the cutting element is caused to
remove a defect from the stock to be 120
patched, means for feeding patch stock into
the machine, means for severing the patch
stock into predetermined lengths to form
patch plugs, means for transferring a patch
plug from the position in which it is sev-
ered to a position in alignment with the 125
recess formed by the cutting element,
means for forcing a patch plug into the
recess formed by the cutting element, and

means for moving the said forcing means to a position in alignment with the said recess and for effecting the forcing action thereof.

5 42. A machine of the class described comprising a recess cutting element, means whereby the cutting element is caused to remove a defect from the stock to be patched, means for feeding patch stock into the machine, means for severing the patch stock into predetermined lengths to form patch plugs, a plunger for forcing a patch plug down into the recess formed by the cutting element, carrier plates for moving the said plunger to a position in alignment with the said recess and means movable through a portion of the movement thereof to effect a movement of the said plates and through an additional movement thereof to effect a 20 plunging action of the said plunger.

43. A machine of the class described comprising a recess cutting element, means whereby the cutting element is caused to remove a defect from the stock to be patched, 25 means for feeding patch stock into the machine, means for severing the patch stock into predetermined lengths to form patch plugs, a plunger for forcing a patch plug down into the recess formed by the cutting element, carrier plates for moving the said plunger to a position in alignment with the said recess, means movable through a portion of the movement thereof to effect a movement of the said plates and through 35 an additional movement thereof to effect a plunging action of the said plunger, and means for locking the said movable means to cooperation with said plates and for automatically releasing the same from said 40 locked relation for effecting the said portion of movement thereof and the said additional movement thereof.

44. A machine of the class described comprising a recess cutting element, means whereby the cutting element is caused to remove a defect from the stock to be patched, 45 means for feeding patch stock into the machine, means for severing the patch stock into predetermined lengths to form patch plugs, means for transferring a patch plug from the position in which it is severed to a position in alignment with the recess formed by the cutting element, means movable in the same plane with the cutting element for forcing a patch plug into the recess formed by the cutting element, and means for moving the said forcing means to a position in alignment with the said recess and for effecting the forcing action thereof and in timed relation to succeed the removal of the cutting element and the transferring of the patch plug.

45. A machine of the class described comprising a recess cutting element, means whereby the cutting element is caused to remove a defect from the stock to be patched, 50 means for feeding patch stock into the machine, means for severing the patch stock into predetermined lengths to form patch plugs, means for transferring a patch plug from the position in which it is severed to a position in alignment with the recess formed by the cutting element, a plunger for forcing a patch plug down into the recess formed by the cutting element, carrier plates for moving the said plunger to a position in alignment with the said removed portion, means movable through a portion of the movement thereof to effect a movement 55 of the said plates and through an additional movement thereof to effect a plunging action of the said plunger, and means for locking the said movable means to cooperation with said plates and for automatically re-

leasing the same from said locked relation 65 for effecting the said portion of movement thereof and the said additional movement thereof.

45. A machine of the class described comprising a recess cutting element, means 70 whereby the cutting element is caused to remove a defect from the stock to be patched, means for feeding patch stock into the machine, means for severing the patch stock into predetermined lengths to form patch 75 plugs, a plunger for forcing a patch plug down into the recess formed by the cutting element, carrier plates for moving the said plunger to a position in alignment with the said recess, means movable through a portion 80 of the movement thereof to effect a movement of the said plates and through an additional movement thereof to effect a plunging action of the said plunger, means for locking the said movable means to cooperation with said plates and for automatically releasing the same from said 85 locked relation for effecting the said portion of movement thereof and the said additional movement thereof, means for laterally adjusting the plunger, and means for adjusting the stroke of the plunger.

46. A machine of the class described comprising a recess cutting element, means whereby the cutting element is caused to remove a defect from the stock to be patched, 90 means for removing the cutting element after it has removed the defect means for feeding patch stock into the machine, means for severing the patch stock into predetermined lengths to form patch plugs, means for transferring a patch plug from the position in which it is severed to a position in alignment with the recess formed by the cutting element, means movable in the same plane with the cutting element for forcing a patch plug into the recess formed by the cutting element, and means for moving the said forcing means to a position in alignment with the said recess and for effecting the forcing action thereof and in timed relation to succeed the removal of the cutting element and the transferring of the patch plug.

47. A machine of the class described comprising a recess cutting element, means whereby the cutting element is caused to remove a defect from the stock to be patched, 110 means for removing the cutting element after it has removed the defect and for returning the same to normal position after a single cycle of operation of the machine, means for cushioning the return movement of the cutting element, means for feeding patch stock into the machine, means for severing the patch stock into predetermined lengths to form patch plugs, means movable 115 in the same plane with the cutting element

- for forcing a patch plug into the recess formed by the cutting element, and means for moving the said forcing means to a position in alignment with the said recess and
- 5 for effecting the forcing action thereof and in timed relation to succeed the removal of the cutting element and the transferring of the plug.
48. A machine of the class described comprising a recess cutting element for cutting and removing the defects from the same surface of the stock to be patched, thus providing a recess in the surface only of said stock, means whereby the cutting element
- 10 is caused to remove a defect from the stock to be patched, means for feeding patch stock into the machine, a knife mechanism for severing the patch stock into predetermined lengths to form patch plugs, a cam and lever mechanism for moving the knife mechanism in the severing direction, spring actuated means for returning the knife mechanism to the normal position, and means for forcing the patch plug into the
- 15 recess formed by the cutting element.
49. A machine of the class described comprising a recess cutting element for cutting and removing the defects from the same surface of the stock to be patched, thus providing a recess in the surface only of said stock, means whereby the cutting element is caused to remove a defect from the stock to be patched, means for removing the cutting element upwardly after effecting the
- 20 removal of the defect, means for feeding patch stock into the machine, a knife mechanism for severing the patch stock into predetermined lengths to form patch plugs, a cam and lever mechanism caused to function by reason of the upward movement of the cutting element for moving the knife mechanism in the severing direction, spring actuated means for returning the knife mechanism to the normal position, and
- 25 means for forcing the patch plug into the recess formed by the cutting element.
50. A machine of the class described comprising a recess cutting element, means whereby the cutting element is caused to remove a defect from the stock to be patched, means for removing the cutting element upwardly after effecting the removal of the defect, means for feeding patch stock into the machine, a knife mechanism for severing the patch stock into predetermined lengths to form patch plugs, a cam and lever mechanism caused to function by reason of the upward movement of the cutting element for moving the knife mechanism in the severing direction, a retractile detent mounted in the said lever and adapted to engage the knife mechanism to move the same, means for automatically releasing the said detent from engagement with the knife mechanism
- 30 after the desired stroke has been effected,
- spring actuated means for returning the knife mechanism to the normal position, and means for forcing the patch plug into the recess formed by the cutting element.
51. A machine of the class described comprising a recess cutting saw adapted for cutting and removing defects from the same surface of the stock to be patched, thus providing a recess in the surface only of said stock, means whereby the cutting element is caused to remove a defect from the stock to be patched, means for feeding patch stock into the machine, means for severing the patch stock into predetermined lengths to form patch plugs, means for forcing a patch plug into the recess formed by the cutting element, and means whereby the position of the recess cutting saw may be adjusted to compensate for wear thereof to retain the desired effective cutting area of said saw.
52. A machine of the class described comprising a recess cutting element adapted to remove defects from the face of the stock to be patched, means for feeding the stock to be patched to the cutting element, means for feeding patching stock into the machine, corrugated rollers for applying an adhesive substance to the patching stock while being fed, means for severing the patching stock in units of length equivalent to the recess formed by the cutting element in removing the defects, and means for inserting the patch into the said recess.
53. A machine of the class described comprising a recess cutting element adapted to remove defects from the face of the stock to be patched, means for feeding the stock to be patched to the cutting element, means for feeding patching stock into the machine, means including a liquid adhesive container and corrugated rollers rotatable therein for applying an adhesive substance to the patching stock while being fed, means for severing the patching stock in units of length equivalent to the recess formed by the cutting element in removing the defects and means for inserting the patch into the said recess.
54. A machine of the class described comprising a recess cutting element, means for feeding the stock to be patched to the cutting element, means for lifting the cutting element upwardly out of cutting relation with the stock to be patched, means for feeding the patching stock into the machine at intervals and in degree equivalent to the length of the patch to be made, corrugated rollers for applying an adhesive substance to the patching stock as it is being fed, means for severing the patching stock into units of length equivalent to the recess formed by the cutting element, means for holding each severed length of patching stock in position for and while being forced into the recess formed by the cutting element, the said

holding means including longitudinally corrugated portions for engaging each cut patch length after it has had adhesive substance applied thereto, and means for forcing the said patching stock into said recess.

55. A machine of the class described comprising a recess cutting element, means for feeding the stock to be patched to the cutting element, means for lifting the cutting element upwardly out of cutting relation with the stock to be patched, means for feeding patching stock into the machine at intervals and in degree equivalent to the 10 length of the patch to be made, means including a liquid adhesive container and cor-

rugated rollers rotatable therein for applying an adhesive substance to the patching stock as it is being fed, means for severing the patching stock into units of length 20 equivalent to the recess formed by the cutting element, means for holding said severed length of patching stock in position for and while being forced into the recess formed by the cutting element, the said holding means including longitudinally corrugated portions for engaging each cut patch length after it has had adhesive substance applied thereto, and means for forcing the said patching stock into said recess. 25

MARVIN EARL STEGER.
